UNITED STATES PATENT OFFICE.

JOHN HENRY JUNGEMANN, OF WOLSEY, SOUTH DAKOTA.

GATE-LATCH.

1,264,084.

Specification of Letters Patent. Patented Apr. 23, 1918.

Application filed December 15, 1917. Serial No. 207,254.

To all whom it may concern:

Be it known that I, JOHN HENRY JUNGEMANN, a citizen of the United States, and a resident of Wolsey, in the county of Beadle 5 and State of South Dakota, have invented a new and Improved Gate-Latch, of which the following is a full, clear, and exact description.

My invention although capable of other 10 uses is more particularly intended for embodiment in a gate latch of the type in which a latch bar is adapted to be guided into latched engagement with a strike plate by means of guide surfaces on the latter.

15 An object of my invention is to provide an efficient latch of the type indicated and including a pivoted spring-pressed latch bar movable for unlatching, by a push rod, and a latch plate presenting a recess or inverted notch at the under side, to which the latch bar is guided and into which it is automatically pressed in the closing of the gate.

Reference is to be had to the accompanying 25 drawings forming a part of this specification in which similar reference characters indicate corresponding parts in all the views, it being understood that the drawings are merely illustrative of one example 30 of the invention.

Figure 1 is a perspective view showing the latch and strike plate applied respectively to a gate and gate post;

Fig. 2 is a side elevation partly in vertical section on the line 2—2, Fig. 3, the gate being in the latched position;

Fig. 3 is a face view of the strike plate and a portion of the gate post;

Fig. 4 is a horizontal section on the line 40 4—4 Fig. 2.

In carrying out my invention in accordance with the illustrated example, the gate elements of the latch include a frame or yoke 10 secured to the gate A by screws 10^a 45 or the like, to which frame a vertically rocking latch bar 11 is pivoted at one end as at 12. The latch bar 11 extends through a keeper 14 forming one side of the frame 10 and the free end 13 of said latch bar 50 projects through said keeper and beyond the edge of the gate. The keeper 14 in the preferred form of the invention constitutes a spring pocket or housing for a coil spring 15 which is seated in the bottom of the 55 pocket and bears at its upper end against the latch bar 11 normally tending to hold

the same raised, which is the latching position. The latch bar 11 is adapted to be depressed against the pressure of the spring 15 through the medium of a vertical push 60 rod 16 having a suitable handle 17 at the top, said rod being pivotally connected at its lower end as at 16^a to the latch bar.

The strike plate 18 to coact with the latch bar 11 is secured to the gate post B which 65 preferably has a cross piece b to receive the strike plate. At the center the latch plate arches or otherwise is given a formation to produce at the under side a flaring inverted notch 19. To guide the latch to the recess 70 19 the strike plate 18 is provided with arms 20 at each side of the notch and extending outwardly and upwardly, whereby to present at the under side guides surfaces 21. The strike plate is secured to the gate post 75 in any suitable manner as by screws 22, said screws passing through bosses 23 on the back of the plate, which bosses serve to space the strike plate from the face of the post. The numeral 24 indicates a strap to guide 80 and retain the push rod 16, the strap being suitably secured as by screws 25 to the gate A.

With the described arrangement when the gate is closed the latch bar 11 will engage 85 either one of the guide surfaces 21 according to the direction to which the gate is swung and will thereby be guided toward the inverted recess 19 and as the guide surfaces 21 merge into the flaring walls of the 90 said recess, the spring 15 will force the latch bar upwardly into the recess when the gate reaches the closed position.

I would state in conclusion that while the illustrated example constitutes a practical 95 embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. In a gate latch, a frame adapted to be 105 secured to a gate, a latch bar pivoted at its inner end to the said frame, a keeper on the frame at the front end through which the latch bar extends, said keeper constituting a spring pocket, a coil spring housed in said 110 pocket and exerting its pressure against the latch bar at the under side thereof, means

to depress the latch bar against the pressure of the spring, and a strike plate adapted to be secured to a gate post, said strike plate presenting at the under side a flaring inverted notch, and side arms extending oppositely at each side of the notch, said arms presenting curved guide surfaces at the under side thereof merging into the flaring walls of the notch.

10 2. In a gate latch, a pivoted latch bar,

means to mount the same on a gate, spring means acting to press the latch bar upwardly, and a latch plate presenting an inverted recess at the under side and guide arms extending oppositely at each side of 15 the notch adapted to engage the top surface of the latch bar to guide the latch bar to said notch.

JOHN HENRY JUNGEMANN.
